JOURNAL BOX LID STRUCTURE

Theodore R. Weber, Latrobe, Pa., assignor to
American Locomotive Company, New York,
N. Y., a corporation of New York

Application March 21, 1941, Serial No. 384,464

7 Claims. (Cl. 308—47)

This invention relates to journal box lid structures.

An object of the present invention is to provide a journal box lid structure having flexible characteristics adapting the lid to bear evenly against the journal box, the spring means to bear evenly against the box lug and the hood to bear evenly against the hinge pintle.

A further object is to provide, in the aforementioned lid structure, novel means for centralizing the lid-closing pressure on the central portion of the lid.

A further object is to provide means for facilitating assemblage and disassemblage of the lid structure with the journal box.

Other and further objects of this invention will appear from the following description, the accompanying drawings and the appended claims.

Referring to the drawings forming a part of the present application, Figure 1 is a front elevation of a journal box lid structure involving the present invention, a journal box being indicated in dot and dash lines; Fig. 2 is a section on the line II—II of Fig. 1, parts being shown in full; Fig. 3 is a front elevation of the lid, the connecting post assembled therewith being shown in section; Fig. 4 is a partial sectional view, similar to the corresponding portion of Fig. 2, showing a modification of the invention; Fig. 5 is an enlarged fragmental plan view of a portion of the lid structure of Fig. 2, showing the application of an assembling and disassembling tool; Fig. 6 is an end view of the structure of Fig. 5; Fig. 7 is, at the left, a front elevation, and, at the right, a section on the line VII—VII of Fig. 8, showing another modification of the invention, the journal box being indicated in dot and dash lines; Fig. 8 is a section on the line VIII—VIII of Fig. 7, parts being shown in full, an assembling and disassembling wedge being shown in dot and dash lines; Fig. 9 is a view, similar to Fig. 3, of the lid of Fig. 7; and Fig. 10 is a partial sectional view, similar to Fig. 4, showing another modification of the invention.

Referring to Figs. 1-3, the journal box lid structure there shown, indicated generally by the reference numeral 1, comprises a lid 2, a hood 3, spring means 4 disposed between the hood and lid, a post 5 connecting the hood and lid, and a hinge pintle 6 for securing the structure to a cam lug 7 of a journal box 8.

The lid closes the open face of the journal box in the usual manner. At its central portion is a depression 9 and a retainer 10, having an orifice 11, the retainer being secured to the side walls 55

of the depression, as by welding, thereby forming a chamber 12 between the retainer and wall of the depression. The retainer extends outwardly at its central portion, forming an inwardly directed concave seat 13 on its inner face and an outwardly directed convex portion 14 on its outer face, for a purpose presently to appear. When the lid is made of pressed steel, the depression and concave seat may be pressed out in a well-known manner. If desired, the concave seat can be formed directly in the lid itself, thus eliminating the separate retainer 10 welded to the lid and the depression 9 formed in the lid. Such a construction is shown in Fig. 4, wherein the central portion of the lid 2' extends outwardly providing the concave seat 13' and convex portion 14', there being no depressed part of the lid extending to the rear of the post. Otherwise the structures of Figs. 2 and 4 are similar and only the structure of Fig. 2 will be hereinafter described.

The hood is pivotally mounted on the pintle by orificed ears 15 and the top wall 16 of the hood covers the lug 7, in the usual manner. A semi-circular outwardly extending flange 17 is formed adjacent the rear margin of the orifice of each ear 15 to provide additional bearing surface against the pintle 6. The flange is widest at its rearmost point and narrows as it approaches its forward ends, at which ends it merges with the side wall of the hood. The pintle 6 is specially constructed to coact with the flanges 17, preventing rotation of the pintle, as is more fully set forth in my copending application Serial No. 376,132, filed January 27, 1941, this feature forming no part of the present invention.

The hood further includes, at its central portion, a coil spring seat 18, which may be formed by pressing out the central portion when the hood is made of pressed steel, an orifice 19 near its lower end, and an orifice 20 in its top wall, all for purposes presently to appear.

The hood, as aforesaid, is connected to the lid by the post 5, which stands outwardly from the lid substantially perpendicular thereto, the outer end of the post being reduced, extending through the orifice 19, and being headed to connect it rigidly to the hood. The lid is connected to the box only through this connection with the hood. A head 21, having an outwardly directed convex face 22, is formed on the inner end of the post, the head being disposed in the chamber 12 with the face 22 in engagement with the seat 13, providing a universal joint connection between the post and lid, permitting relative tilting movement between the hood and lid. The post ex-

tends through the orifice 11 with sufficient clearance, and the head 21 has sufficient clearance in the chamber 12 to permit such tilting. The universal joint thereby formed is close to the plane of the lid and box face. Thus tilting of the lid will not result in any appreciable lateral or longitudinal shift of the lid.

The spring means 4 includes a plate 23, bearing at its upper end against the lug 7, and coil springs 24, the coil springs, which are disposed one within the other, engaging at their inner ends the plate and at their outer ends the seat 18, providing a flexible connection between the plate and hood, permitting relative tilting movement therebetween. A boss 25 is formed on the plate opposite the seat 18, the seat and boss preventing displacement movement of the coil springs. The coil springs, by means of the boss, and the post prevent the plate from moving laterally off the box lug.

A portion of the lower end of the plate 23 extends outwardly providing an inwardly directed concave seat 26 engaging the portion 14 and providing a universal joint connection between the plate and lid, permitting relative tilting movement therebetween. An orifice 27 is formed in the seat 26 through which the post freely passes, the orifice being larger than the diameter of the post. Obviously in assembling the parts of the lid structure, the post head must be disposed in the chamber before the retainer 10 is welded to the lid and the plate and hood must then be associated with the post and the outer end of the post finally headed. The post permanently secures the lid, plate and hood together, preventing their accidental disassembly.

The universal joints and flexible connection, permitting relative tilting movements of the hood, plate and lid, enable the lid to bear evenly against the box, the plate against the lug and the hood ears against the pintle, even though one or more of these parts is imperfectly formed. For instance, the plate may seat evenly on the face of the box lug even though this face is out of parallel with the lug orifice.

The coil springs exert an outwardly directed force on the hood and an inwardly directed force on the plate, the plate transmitting the force to the lid at its central portion and holding the lid firmly on the box. The plate is disposed close to and approximately parallel to the lid which prevents wearing movements of the upper end of the plate against the box lug during vibration movements of the lid structure when in service.

The upper end of the plate includes an extension 28 which extends above the top face of the lug into a space 29 provided between the top face of the lug and the opposite under face of the top wall 16 of the hood. A rivet 30 is secured to the top wall of the hood, being disposed in the orifice 20, and has a cylindrical head 31 depending into the space 29 for coaction with an assembling and disassembling tool 32, best shown in Figs. 5 and 6.

The tool 32 is made of cylindrical wire, but may be of any suitable cross section, such for instance as rectangular. It includes an open link-like portion 33 having a finger 34 extending, when the tool is assembled with the lid structure, over the upper face of the top wall of the hood, and another finger 35 extending beneath the under face of the top wall of the hood, the fingers being connected by a U-shaped portion 36. The tool further includes a curved hook portion 37 extending from the end of the finger 35, the

plane of the link-like portion being at right angles to the plane of the hook portion.

The tool is, in the case of a new lid structure, applied by the manufacturer so that the lid structure may later be assembled with a journal box without the use of any other tool. To apply the tool, the manufacturer must clamp the plate toward the hood, thereby compressing the coil springs, and then wind the hook portion around the cylindrical rivet head, the finger 34 acting as a handle to facilitate the rotation of the tool. The clamp is then removed and the spring plate allowed to press against the tool, holding it firmly against the cylindrical head. The open link-like portion prevents the tool from dropping below the rivet. The tool holds the plate toward the hood sufficiently so that the hood ear orifices can be aligned with the lug orifice, and the pintle inserted without interference from the spring means.

To remove the tool after assemblage of the lid structure with the journal box, it is merely necessary to open the lid sufficiently for the plate to be moved toward the hood by the box lug thus relieving pressure on the tool, and then rotating the tool in a disengaging direction. If it should be desired at any time thereafter to remove the lid structure from the box, the lid structure may be partially opened as above described and the tool applied once more, as the rivet remains with the hood after removal of the tool.

Referring to Figs. 7-9, the lid structure there shown has the same advantages as the afore-described lid structure, but differs therefrom in a few structural details. Referring to Fig. 8, it will be seen that an outwardly directed concave seat 38 is formed in the bottom of the lid depression 39. The post 40, at its inner end, has a head 41 providing an inwardly directed convex face 42 which is disposed in engagement with the seat 38, providing a universal joint between the post and lid 43. The coil springs 44 are disposed between the lower end of the plate 45, against which they bear, and the lid, the post passing through the center of the coil springs, which bear at their inner ends against a washer 46 carried by the post, thereby providing a flexible connection between the plate and lid. The coil springs exert an inwardly directed force against the post head, by means of the washer 46, and the post head transmits the force to the lid, holding it securely on the box. The post head and washer 46 are both disposed in the chamber 47 provided by the depression 39 and the retainer 48 secured thereto, and the orifice in the retainer is sufficiently large to permit the coil springs to extend therethrough.

The plate and hood 49 engage at their central portions, the hood having a ball portion 50 and the plate having a socket portion 51, providing a universal joint between the plate and hood. Thus this modification of the invention employs a universal joint between the hood and plate and between the hood and lid, and a flexible connection between the plate and lid, whereas in the structure of Figs. 1-4 a flexible connection was provided between the hood and plate and universal joints were provided between the hood and lid and between the plate and lid.

A wedge 52 is employed to facilitate assembling and disassembly of the lid structure with the journal box. The wedge is inserted through a slot 53 formed in the bottom wall of the hood and forced between the lower end of the plate and the opposite portion of the hood. The plate

acts as a lever, fulcruming about the ball portion 50, the top of the plate moving toward the hood as the wedge forces the bottom of the plate away from it. Thus the wedge holds the top of plate 45 in the same position as the tool 32 holds the plate 23.

In the case of new lid structures, the manufacturer can assemble the wedge with the lid structure, and the lid structure can then be shipped to the place where it will be used, ready for assemblage with a journal box. Pressure can be taken off the wedge, when it is desired to remove the wedge after assemblage of the lid structure with the box, by partially opening the lid structure, as was done in the case of the lid structure of Figs. 1-3.

The structure of Figs. 7-9 has the further advantage that the post also secures the coil springs permanently with the other parts of the lid structure, and the coil spring may be partially compressed even when the lid structure is not assembled with the box, as outward movement of the lower end of the plate is limited by the space between it and the hood, and the compressed springs will be held between the plate lower end and the washer.

Fig. 10 shows another modification of the invention. Here the type of lid and post of the lid structure of Figs. 1-3 and the hood and spring means of the lid structure of Figs. 7-9 are employed. Of course the lid shown in Fig. 4 may be employed, if desired, in place of the lid shown in Fig. 10. The lid structure of Fig. 10 has all the advantages of the aforescribed lid structures and is similar to the lid structure of Figs. 7-9 in that the universal joints are provided between the hood and plate and between the hood and lid, the flexible connection being between the plate and lid. However, it will be noted that the coil spring seats against the retainer, instead of against the bolt head (Fig. 8), thus directly holding the lid against the box. Only one coil spring is shown, although two may be employed if desired. A reinforcing flange 54 is employed about the orifice in the hood through which the post passes. This flange may be employed in the other structures if desired. It is contemplated that cast hoods may be employed in place of the pressed steel hoods, and in such a case the flange 54 would probably be employed.

While there have been hereinbefore described approved embodiments of this invention, it will be understood that many and various changes and modification in form, arrangement of parts and details of construction may be made thereto without departing from the spirit of the invention and that all such changes and modifications as fall within the scope of the appended claims are contemplated as a part of this invention.

The invention claimed and desired to be secured by Letters Patent is:

1. The combination of a journal box having an opening and a hinge lug; a lid member covering said opening; a hood connected to said hinge lug for swinging movement toward and away from said box; a connecting member, disposed substantially perpendicular with respect to the plane of said lid member, secured at its inner end to said lid member and at its outer end to said hood; and spring means operatively disposed between said hood and lid member, engaging at one end said lug, at an intermediate point said hood, and at the other end one of said members, thereby pressing said lid member upon said box, said connecting member passing freely through

said spring means for securing said lid member, hood and spring means together.

2. A closure for an open-faced journal box having a cam lug on the top thereof, said closure comprising a pintle adapted to be mounted in said lug for hingedly assembling said closure with said box; a hood member having on its upper end portion, eyes mounting said hood member on said pintle at the end portions thereof; a lid member for covering said box opening; a plate disposed between said members having an upper end portion for spring-pressed engagement with said cam lug; a spring operatively mounted between said plate and one of said members; a post outwardly standing from said lid member, connecting said lid member to said hood member, said post being connected at its inner end to said lid member adjacent the central portion thereof, and at its outer end to said hood member at the lower end portion thereof; and a flexible joint providing one of said post connections, said plate being flexibly connected between its ends to said hood member and flexibly connected at its lower end to said lid member, said spring forming one of said plate flexible connections and a universal joint forming the other of said plate flexible connections, said plate being loosely mounted at its lower end portion on said post in spaced relation to said hood member, and said spring being energized, exerting an outwardly directed force upon said hood member and an inwardly directed force upon said lid member, when said closure is assembled with said box, one of said forces being applied through said plate, whereby said plate will be held spring-pressed against said cam lug and said lid member when closed will be held spring-pressed against said box, said flexible connections insuring even bearing of said eyes against said pintle, said plate upon said cam lug and said lid member upon said box.

3. A closure for an open-faced journal box having a cam lug on the top thereof, said closure comprising a pintle adapted to be mounted in said lug for hingedly assembling said closure with said box; a hood having on its upper end portion, eyes mounting said hood on said pintle at the end portions thereof; a lid for covering said box opening; a plate disposed between said hood and lid, having an upper end portion for spring-pressed engagement with said cam lug; an energized spring operatively mounted between said plate and lid; a post outwardly standing from said lid, connecting said lid to said hood, said post being connected at its inner end to said lid adjacent the central portion thereof, and at its outer end to said hood at the lower end portion thereof; and a universal joint providing one of said post connections, said plate being connected between its ends by another universal joint to said hood and flexibly connected at its lower end by said spring to said lid, said plate being loosely mounted at its lower end portion on said post in spaced relation to said hood, and said spring exerting an outwardly directed force upon said hood and an inwardly directed force upon said lid when said closure is assembled with said box, said force upon said hood being applied through said plate, whereby said plate will be held spring-pressed against said cam lug and said lid when closed will be held spring-pressed against said box, said universal joints and flexible connection insuring even bearing of said eyes against said pintle, said plate upon said cam lug and said lid upon said box.

4. A closure for an open-faced journal box having a cam lug on the top thereof, said closure comprising a pintle adapted to be mounted in said lug for hingedly assembling said closure with said box; a hood having on its upper end portion, eyes mounting said hood on said pintle at the end portions thereof; a lid for covering said box opening; a plate disposed between said hood and lid having an upper end portion for spring-pressed engagement with said cam lug; an energized spring operatively mounted between said plate and lid; and a post outwardly standing from said lid, connecting said lid to said hood, said post being connected at its inner end by a universal joint to said lid adjacent the central portion thereof, and at its outer end to said hood at the lower end portion thereof, said plate being connected between its ends by another universal joint to said hood and flexibly connected at its lower end by said spring to said lid, said plate being loosely mounted at its lower end portion on said post in spaced relation to said hood, and said spring exerting an outwardly directed force upon said hood and an inwardly directed force upon said lid when said closure is assembled with said box, said force upon said hood being applied through said plate, whereby said plate will be held spring-pressed against said cam lug and said lid when closed will be held spring-pressed against said box, said universal joints and flexible connection insuring even bearing of said eyes against said pintle, said plate upon said cam lug and said lid upon said box.

5. A closure for an open-faced journal box having a cam lug on the top thereof, said closure comprising a pintle adapted to be mounted in said lug for hingedly assembling said closure with said box; a hood having on its upper end portion, eyes mounting said hood on said pintle at the end portions thereof; a lid for covering said box opening having an outwardly directed concave seat; a plate disposed between said hood and lid having an upper end portion for spring-pressed engagement with said cam lug; an energized spring operatively mounted between said plate and lid; and a post outwardly standing from said lid, connecting said lid to said hood, said post being connected at its outer end to said hood at the lower end portion thereof, and at its inner end having an inwardly directed convex head, disposed in said seat, said head and seat providing a universal joint connecting said post inner end to said lid, said plate being connected between its ends by another universal joint to said hood and flexibly connected at its lower end by said spring to said lid, said plate being loosely mounted at its lower end portion on said post in spaced relation to said hood, and said spring exerting an outwardly directed force upon said hood and an inwardly directed force upon said lid when said closure is assembled with said box, said force upon said hood being applied through said plate, whereby said plate will be held spring-pressed against said cam lug and said lid when closed will be held spring-pressed against said box, said universal joints and flexible connection insuring even bearing of said eyes against said pintle, said plate upon said cam lug and said lid upon said box.

6. A closure for an open-faced journal box having a cam lug on the top thereof, said closure comprising a pintle adapted to be mounted in

said lug for hingedly assembling said closure with said box; a hood having on its upper end portion, eyes mounting said hood on said pintle at the end portions thereof; a lid for covering said box opening having an inwardly directed concave seat; a plate disposed between said hood and lid having an upper end portion for spring-pressed engagement with said cam lug; an energized spring operatively mounted between said plate and lid; and a post outwardly standing from said lid, connecting said lid to said hood, said post being connected at its outer end to said hood at the lower end portion thereof, and at its inner end having an outwardly directed convex head, disposed in said seat, said head and seat providing a universal joint connecting said post inner end to said lid, said plate being connected between its ends by another universal joint to said hood and flexibly connected at its lower end by said spring to said lid, said plate being loosely mounted at its lower end portion on said post in spaced relation to said hood, and said spring exerting an outwardly directed force upon said hood and an inwardly directed force upon said lid when said closure is assembled with said box, said force upon said hood being applied through said plate, whereby said plate will be held spring-pressed against said cam lug and said lid when closed will be held spring-pressed against said box, said universal joints and flexible connection insuring even bearing of said eyes against said pintle, said plate upon said cam lug and said lid upon said box.

7. A closure for an open-faced journal box having a cam lug on the top thereof, said closure comprising a pintle adapted to be mounted in said lug for hingedly assembling said closure with said box; a hood having on its upper end portion, eyes mounting said hood on said pintle at the end portions thereof; a lid for covering said box opening having an inwardly directed concave seat and an outwardly directed convex portion; a plate disposed between said hood and lid having an upper end portion for spring-pressed engagement with said cam lug, and, at its lower end, an inwardly directed concave seat; a spring operatively mounted between said plate and hood; and a post outwardly standing from said lid, connecting said lid to said hood, said post being connected at its outer end to said hood at the lower end portion thereof, and at its inner end having an outwardly directed convex head disposed in said lid seat, said head and lid seat providing a universal joint connecting said post inner end to said lid, said plate being flexibly connected between its ends by said spring to said hood, said plate being loosely mounted at its lower end portion on said post in spaced relation to said hood with its concave seat mounted on said lid convex portion, providing a universal joint connection between said plate and lid, and said spring being energized, exerting an outwardly directed force upon said hood and an inwardly directed force upon said plate when said closure is assembled with said box, whereby said plate will be held spring-pressed against said cam lug and lid, and said lid when closed will be held spring-pressed against said box, said universal joints and flexible connection insuring even bearing of said eyes against said pintle, said plate upon said cam lug and said lid upon said box.

THEODORE R. WEBER.
